UNITED STATES PATENT OFFICE.

WILLIAM M. SMITH, OF MERIDEN, CONNECTICUT, ASSIGNOR TO THE MERIDEN BRITANNIA COMPANY, OF SAME PLACE.

DESIGN FOR A COFFIN-SCREW ESCUTCHEON.

SPECIFICATION forming part of Design No. 15,043, dated June 3, 1884.

Application filed March 17, 1884. Term of patent 14 years.

To all whom it may concern:

Be it known that I, WM. M. SMITH, of Meriden, in the county of New Haven and State of Connecticut, have invented a new Design for 5 a Coffin-Screw Escutcheon; and I do hereby declare the following, when taken in connection with accompanying drawing and the letters of reference marked thereon, to be a full, clear, and exact description of the same, and which 10 said drawing constitutes part of this specification and represents a perspective view.

This invention relates to a design for the plate which is set upon the top of a coffin, and through which the securing-screw passes; and 15 it consists in the configuration shown in the accompanying illustration and hereinafter described.

The plate is oblong—its two ends semicircular. Between the semicircular ends and on 20 each edge is the representation of a cord, *b*,

which appears to spring from beneath the ends—that is, the ends appear as a cap covering the cord which passes around the end. The surface of the ends is ornamented by radiating lines representing a fan ornament, and 25 the surface between the corded sides is also ornamented by panel-work and tracery.

I claim—

The herein-described design for a coffin-screw escutcheon, consisting of a plate having its 30 sides parallel and ornamented by the representation of a cord, the two ends having a fan-shaped ornament represented as overlying the cords at the ends, the surface between the cords ornamented by panel-work and tracery, as 35 shown in the accompanying illustration.

WILLIAM M. SMITH.
